(57) **CLAIM**

The ornamental design for a water purification system in the shape of a water droplet, as shown and described.

DESCRIPTION

FIG. 1 is a front left perspective view of a water purification system in the shape of a water droplet, showing the present design.

FIG. 2 is a front view of the water purification system in the shape of a water droplet, showing the present design.

FIG. 3 is a rear view of the water purification system in the shape of a water droplet, showing the present design.

FIG. 4 is a right-side view of the water purification system in the shape of a water droplet, showing the present design.

FIG. 5 is a left-side view of the water purification system in the shape of a water droplet, showing the present design.

FIG. 6 is a top view of the water purification system in the shape of a water droplet, showing the present design.

FIG. 7 is a bottom view of the water purification system in the shape of a water droplet, showing the present design; and,

FIG. 8 shows the interior of the water purification system in the shape of a water droplet, showing the present design. The interior portions of the water purification system in the shape of a water droplet shown in broken lines form no part of the claimed design.

1 Claim, 7 Drawing Sheets
